UNITED STATES PATENT OFFICE.

CHARLES H. HAISLEY, OF MUNCIE, INDIANA.

WIRE-FENCE MACHINE.

1,163,404.

Specification of Letters Patent.

Patented Dec. 7, 1915.

Application filed April 24, 1913. Serial No. 763,369.

To all whom it may concern:

Be it known that I, CHARLES H. HAISLEY, a citizen of the United States, residing at Muncie, in the county of Delaware and State 5 of Indiana, have invented certain new and useful Improvements in Wire-Fence Machines, of which the following is a specification.

This invention has reference to certain new 10 and useful improvements in wire fence machines.

The invention has for one of its objects to produce a machine for automatically making a wire fence or fence fabric having alternate 15 long and short stays, whereby there is combined in one roll or stretch of fence, a field and a hog fence.

The invention has for a further object to improve the wire connecting devices in a 20 wire fence machine, whereby the devices for connecting the ends of the short stays with an intermediate wire of the fence will, with each alternate operation of the machine connect the intermediate body portion of a long stay with the corresponding wire to which 25 the end of the short stay is connected.

That the invention may be more fully understood reference is had to the accompanying drawings, in which:—

Figure 1 is an elevation, partly in section, 30 of so much of a wire fence machine as is necessary to show the application of my improvements; Fig. 2 is a plan of what is shown in Fig. 1, with the addition of certain 35 stay transferring devices; Fig. 3 is a view looking at the right hand end of Fig. 1, showing only the controlling means for the stay feeding mechanism; Fig. 4 is an enlarged top plan view of a wire connecting 40 device used for connecting the end of a short stay to an intermediate line wire and for alternately connecting the intermediate body portion of a long stay to the corresponding intermediate line wire; Fig. 5 is an elevation 45 partly in section, of the parts shown in Fig. 4; Fig. 6 shows a plurality of views of the 50 device shown in Fig. 4, said views illustrating successive steps in connecting the intermediate body portion of a long stay to the same intermediate line wire, as the ends of 55 the short stays are alternately connected by the same wire connecting device; Fig. 7 is a view similar to Fig. 6, except that there is illustrated the successive steps of connecting 60 the end of a short stay to an intermediate

line wire; Fig. 8 is a plan of a modified form of wire connecting device when used to alternately connect the end of a short stay to an intermediate line wire, and the intermediate body portion of a long stay to the 60 same intermediate line wire; Fig. 9 is an elevation partly in section of the device shown in Fig. 8, and Fig. 10 is a view illustrating a preferred form of fence made on my machine. 65

Like characters of reference denote corresponding parts throughout the figures.

My improvements are best applied to a machine for making a wire fence where the stay wire is one continuous piece from one 70 end to the other and where the intermediate portions of the stay wires, where they intersect with the intermediate line wires of the fence, are looped and such loops wrapped or coiled around said intermediate line wires, in 75 manner seen in Fig. 10. I make no claim to being the first to connect a stay wire to the line wires of a fence, by looping the stay wire at intervals and wrapping or coiling said loops around the line wires. I also 80 make no claim to being the first to produce a fence wherein the stay wires are one continuous piece from end to end, with portions of the stays connected to the line wires, where they intersect, by wrapping portions of the 85 stay wires around said line wires.

What I propose, by my improvements, and what I have actually used, is a machine including a feeding mechanism for feeding a stay length of wire, and a controlling 90 means for said feeding mechanism, whereby said stay feeding mechanism will automatically and alternately feed a long stay wire to extend across the fence from one selvage or margin wire to the other, being connected 95 to all of said wires, and also feed a short stay wire to extend across the fence from one selvage or margin wire, terminating at one of the intermediate line wires of the fence; the ends of the short stays being preferably 100 wrapped by a single continuous wrap around such intermediate line wire, while the intermediate or intersecting body portions of the longer stays are connected to the corresponding intermediate line wire, by first forming a 105 loop in the body of said longer stays and wrapping or coiling said loops around such intermediate line wire.

I do not lay claim to being the first to combine in a fence machine, a mechanism for 110

- making a fence having alternate long and short stays, but I do believe I am the first to use a single stay feeding mechanism which is adapted to feed, first, a long stay wire, and 5 then, a short stay wire, such mechanism being adapted to be adjusted so as to vary the length of such long and short stay wires, so that various heights of fence may be made on the same machine.
- 10 The advantage in manufacturing a fence with alternate long and short stay wires is, that the manufacturer may combine in the one fence a hog and a field fence. The farmer in purchasing a hog fence seeks a 15 low fence with a close mesh, that is, where the stay wires are comparatively close, say, four inches, six inches, or possibly nine inches or twelve inches apart, being a fence to turn the small stock; whereas, when he 20 purchases a field fence, he seeks height, and the stay wires may be twelve or more inches apart. Combining the short and long stay wires in a fence, he may have the close mesh at the bottom, and the wider mesh at the top, 25 having two fences in one at a considerable reduction in cost, made possible owing to the economy in the use of wire when manufacturing the fence.

In the drawings I have illustrated only so 30 much of a machine as will illustrate the application and working of my invention.

1 designates a table or bed-plate of the machine frame in which are journaled a plurality of wire connecting devices 2, preferably of the coiler type. Each device 2 includes a tubular spindle 3 through which strand or line wires A are drawn, by means of the usual pull-out and wrapping devices (not shown) common in machines of this 40 kind; also a coiling or wrapping head 4 journaled in a bushing 5 in the table or bed-plate, and attached to said coiling or wrapping heads, are cap-plates 6. These cap-plates 6 are recessed or slotted as at 7 to receive the rollers 8 revolvably secured on the upper surface of said coiling or wrapping heads and working in the recesses or slots 7 in said cap-plates 6. Said cap-plates are further provided with the slot 9 communicating with said recess or slot 7 and opening 45 out of the peripheral face of said cap-plates, for a purpose to be further explained.

Slidably keyed on the spindles 3, beneath each coiling or wrapping head 4 is a grooved 50 collar 10 and connected with each collar 10 is a pin 11 which normally projects up through an opening in the coiling or wrapping head 4 with its upper end in operative position in the slot 7 of said cap-plate 6. The collars 10 rotate with the spindles 3 and at stated intervals are moved downwardly 55 on said spindles 3 drawing down the pins 11 so that their upper ends are below the upper surface of the coiling or wrapping heads 4. The structure of the spindles, coiling or

wrapping heads, cap-plates, sliding collars and pins are of a well known type in fence machine building, with the exception of the specific slotted construction of cap-plates. The wire connecting devices, as shown, are spaced at graduated distances from each other, which is preferable, but it is understood that said wire connecting devices may be spaced at uniform distances from each other, if desired. 70

I have not shown the driving mechanism for the wire connecting devices, but it is understood that whatever type of mechanism is employed, it will be timed to operate said wire connecting devices in harmony with the remaining mechanisms of the machine. I have in mind that the spindles may be continuously driven, in manner shown in Letters Patent No. 1,047,125 issued to me on the 10th day of December, and intermittently and progressively retract the pins 11; or said spindles may be intermittently and progressively operated by segmental gears in a manner well known in the art of fence machine building. 75

The principle on which the wire connecting devices, in the present instance operate, may be briefly stated as follows: A stay wire B, shown in dotted lines in Fig. 2, being laid across the wire connecting devices between the pins 11 and the strand wires A, is attached to the strand wires by looping the intermediate body portions of said stay wire where it intersects with the strand wires and wrapping or coiling said loops around the strand wires, the ends of the stay wire being wrapped or coiled around the intersecting line wires by a single continuous wrap. A coiling spindle being set in motion the pin 11 will engage with the stay wire producing a loop; such loop being formed before the coiling device has made a complete rotation, when the collar 10, by a suitable means, (not shown) is moved downwardly on its spindle, retracting the pin 11 and releasing it from the loop formed in the stay wire, when said loop is coiled or wrapped around the strand wire A through the continued operation of the coiling or wrapping head. The coilers 95 make preferably two and one half to three 100 rotations. 105

The foregoing operation refers particularly to the connection of the intermediate portions of a stay wire with the intersecting line or strand wires. I will explain hereinafter the change which occurs when connecting or attaching the alternate long and short stays to the line wires of the fence. 110

The feeding devices for the stay wires 115 includes the continuously driven friction gripping wheels 12 and 13, which have meshing gear wheels 14 and 15. Connected with the gear wheel 14 and friction gripping wheel 12 is a gear wheel 16 driven 120

from a gear wheel 17 meshing therewith, and which may be operated from any of the driving parts of the machine. The gear wheels 14 and 15 are constantly in mesh with each other, but the friction surface of the gripping wheels 12 and 13 are normally so spaced from each other as to have no gripping effect on a wire passing therebetween and it is the function of the device to move the wheel 13 into impinging relation with the stay feed wire between it and the surface of the wheel 12 so as to feed the wire to the wire connecting devices. To accomplish this result, the wheel 13 is mounted on an eccentric support and connected therewith is a lever 17. To the rear end of the lever 17 is attached one end of a spring 18, the other end of which is secured to the machine frame. The spring 18 serves to normally hold the wheel 13 from impinging relation with the stay feed wire. Passing through the outer end of the lever 17 is a rod 19, on the upper end of which, is a nut or collar 20 and surrounding this rod between the nut or collar 20 and said lever 17 is a coil spring 21, which acts to maintain the rod 19 in its normal or operative position. To the lower end of the rod 19 is connected a rod 22 which, at its lower end is connected to an arm 23 on a rocker shaft 24. On the opposite end of the rocker shaft 24 is carried an arm 25 to which is connected a bar 26, and said bar 26, at its opposite end, is connected to a lever 27, said lever 27 being pivotally supported at its upper end, and at its lower end carrying a roller or rollers 28 adapted to be intermittently and successively engaged by cams 29 and 30 for moving said lever 27, to reciprocate the bar 26, which in turn will rock the shaft 24 and draw down the rods 22 and 19 for the purpose of oscillating the lever 17 and rock the wheel 13 to cause it to impinge on the stay feed wire lying between the friction surfaces of wheels 12 and 13, the parts being maintained in this same operative relation during the engagement of the cams 29 and 30 with the roller or rollers 28 or the lever 27.

The cams 29 and 30 are segment plates, as shown, so as to be adjustable in connection with the disk 31 to which they may be secured when adjusted. Adjusting the cams 29 and 30 with respect to each other will determine the period of operation of the feed wheel 13 on a stay feed wire, and adjusting the segment plates of each cam 29 or 30 will determine the period of the time that the feed wheels 12 and 13 are operated to project a stay wire and the length of such stay wire. The disk 31 and cams are of course carried by a suitable shaft, and such shaft geared in a suitable manner to certain other machine parts.

When the cam 29 moves the lever 27, the

longer stay wire B', seen in Fig. 10, and extending from one selvage or margin wire to the other, is projected across the line wires A of the fence, and when the cam 30 moves the lever 27, the shorter stay wire B, seen in the same figure is projected across the line wires extending from one selvage or margin wire to one of the intermediate line wires A. During the interval between the engagement of the cams 29 and 30, with the rollers on lever 27, the line wires are advanced in the machine so as to properly space the stay wires. The operation of the shaft carrying the cams 29 and 30, is of course timed with respect to the other operating mechanisms of the machine. It will thus be observed that with the stay feeding device shown, a long or a short stay wire may be alternately fed to the line wires of the fence, and that such parts may be so adjusted that the long stay will extend from one selvage or margin wire to the other, and that the short stay wire will extend from one selvage or margin wire to a certain intermediate line wire. With the completion of a stay length whether long or short, the same are severed by a suitable cutter, not shown, for the stay feed wire.

In Fig. 2 is shown in plan, in a general way, certain stay wire transferring and positioning devices, which form no part of the present invention, except as they coöperate with the stay feeding means to place the stay wires on the cooling or wrapping devices, the same being more generally shown in my Patent No. 1,047,125.

In Figs. 1 and 2 I have shown the coiling or wrapping devices so fixed that short stays may be fed into the machine with their forward ends coiled, either about the sixth intermediate line wire or about the eighth intermediate line wire, depending of course on how the cams 29 and 30 are adjusted with respect to each other, or how the cam segments of each cam are adjusted with respect to each other. In Fig. 2 the machine is shown capable of weaving a ten-bar fence, or a fence with ten line wires, although in Fig. 10, I have shown the fence composed of only eight line wires. To provide for attaching the ends of the short stay wires, by a single wrap, to an intermediate line wire, say for instance where the fence comprises eight bars, as shown in Fig. 10, or where the ends of such short stay wires are attached by a single wrap to the sixth or the eighth intermediate line wire, in a ten-bar fence as provided for in the machine shown in Fig. 2, I employ a removable attachment or attachments which I locate adjacent to or coincident with the coiler or wrapping device through which passes the line wire around which the plain end of the stay wire is to be wrapped, and said attachment is of such construction, as will be explained,

that it will force the end of the stay wire down into the slot 9 of the cap-plate 6 so that the pin 11 and the rollers 8 will operate upon the end of the stay wire to coil it around the line wire A.

The construction of the attachment just referred to takes two different forms; that shown in the general figures and particularly Figs. 4 to 7 and also that form shown in Figs. 8 and 9. In Figs. 4 to 7 the cap-plate 6 is shown with its upper face above the surface of the table or bed-plate 1, whereas in Figs. 8 and 9 the upper face of the cap-plate 6 is flush with the surface of the table or bed-plate 1, being a modification used under certain conditions, as hereinafter described.

The attachment detailed in Figs. 4 and 5 includes the approximately semi-circular ring-like-structure 32 formed with the off-set or shoulder 33 and arranged with the vertical slot 34. When in operative position on the bed-plate or table 1, the attachment partially encircles a cap-plate 6 and is secured in position by feet or supporting members 35 which are bolted or otherwise suitably secured on the bed-plate or table 1. The lower edge of the attachment starting from the vertical wall 36 is beveled or arranged with a sloping face 37, extending from said wall 36 a suitable distance. The feet or supporting members 35 support the attachment with its lower face removed a short distance above the bed-plate or table 1, for a purpose which will be explained.

In Figs. 2 and 4, the coilers or wrapping heads are in their normal or initial position ready to receive a stay wire and just prior to their initial operation which will cause the pins 11 to engage the stay wire. The attachments 32 are so placed that the off-set or shoulder 33 and the corresponding vertical wall 36 are upon diametrically opposite sides of the line wire passing through the coilers and a stay wire laid on the coilers will be between the line wire and pin 11 and across and in front of the shoulder 33 and vertical wall 36, as shown in dotted lines in Fig. 2, and in full lines on the extreme left hand views of Figs. 6 and 7.

When the coiler is placed in motion and when such coiler has made approximately a one quarter turn the pin 11 is brought into contact with the stay wire, and if the engagement of the pin 11 is with an intermediate portion of the stay wire, as in Fig. 6, a loop C will be formed in the stay wire, to be subsequently engaged by the rollers 8, when the pin 11 is retracted and said loop wrapped or coiled about the strand wire; but if it is the end of the stay wire (preferably the shorter stay wire) with which the pin 11 engages, as in Fig. 7, the end of the stay wire will pass under the attachment 32 and

because of the beveled or sloping face 37 will be forced downwardly passing through the slotted opening 9 in the cap-plate 6 and into a position in the slotted opening 7 in said cap-plate to be engaged by the rollers 8, during the further and continued rotation of the coiler, and coiled or wrapped around the line wire, by a single continuous wrap, as distinguished from a "loop" wrap. The sloping face 37 of the attachment is of such a length that the end of the stay wire will be fully within the slotted opening 9 in the cap-plate 6, before the pin 11 is withdrawn, to insure the completion of the stay wrap by the further and continued rotation of the coiler. The vertical slot 34 in the attachment 32 is provided so as to receive the presser foot 38, see Fig. 2, disclosed in my Patent No. 1,047,125 and employed as a guard to prevent the stay wire from becoming dislodged. No claim is made on the presser foot construction in this application.

The attachment 39 detailed in Figs. 8 and 9 differs from that shown in Figs. 4 and 5 to the extent that it is adapted to partially encircle a cap-plate which is set in an annular depression 40 in the bed-plate or table. In this structure the greater portion of the surface of the attachment, and the surface of the cap-plate 6 are flush with the upper surface of the bed-plate or table 1, with the lower face of the attachment removed slightly above the surface of the bushing 5. One end of the attachment slopes upwardly as at 41 being slightly above the surface of the bed-plate or table 1 so that the end of the stay wire will be forced under said sloping end 41 and by such sloping surface forced into the slotted opening 9 in the cap-plate, in manner and for the purposes specifically stated in connection with the structure shown in Figs. 4 and 5. The attachment 39 is secured in place by means of lips 42 which may be bolted or otherwise suitably secured to the bed-plate or table 1.

What I claim is:

1. In a wire fence machine, a stay feeding device, and means for operating said device to cause the same to alternately feed a short stay-wire and a comparatively longer stay-wire.
2. In a wire fence machine, a stay feeding device, means for operating said device to intermittently engage and feed a stay length of wire, said operating means adapted to cause said device to alternately feed a short stay-wire and a comparatively longer stay-wire.
3. In a wire fence machine, a stay feeding device, including a pair of continuously driven feed wheels, said wheels arranged to intermittently impinge upon a stay feed wire for the purpose of feeding a stay length of wire, means for causing said wheels to impinge upon the stay feed wire, said means

operating to alternately cause the feed wheels to first feed a short stay length and then a comparatively longer stay length.

4. In a wire fence machine, a continuously operated stay feeding device, said device arranged to intermittently feed a stay length of wire, and controlling means for causing the device to alternately feed irregular lengths of stay wires.

10 5. In a wire fence machine, a stay feeding device, said device adapted to feed a stay length of wire in a continuous piece and of a length to span two or more line wires of a fence, and controlling means for said feeding device, said controlling means causing said feeding device to alternately feed irregular lengths of stay wires.

6. In a wire fence machine, a stay feeding device, including friction gripping wheels, means for operating said wheels, said wheels arranged to intermittently feed a stay length of wire, lever means for bringing the wheels into impinging relation with a stay feed wire, and a revoluble body including cams for operating said lever means, said cams being unequal for causing said wheels to alternately feed a short stay length and a comparatively longer stay length.

7. In a wire fence machine, a coiling device including a wrapping head and a retractable pin, said pin adapted to engage a stay wire and place it so as to be wrapped around another wire by said wrapping head, an attachment associated with said wrapping head, said attachment having a sloping surface for guiding the stay wire down into said wrapping head as the head is revolved and immediately following the engagement of said wire by said pin.

40 8. In a wire fence machine, a coiling device including a wrapping head, said head being slotted from its periphery inwardly, a retractable pin movable in said head and through the slot therein, said pin adapted to engage a stay wire and place it so as to be wrapped around another wire by said wrapping head, an attachment having a sloping surface for guiding the stay wire down into the slot in said head as the head is revolved and immediately following the engagement of said wire by said pin.

9. In a wire fence machine, a coiling device including a head, a cap-plate secured to said head, said cap-plate being slotted with the slot opening out of the periphery thereof, a retractable pin movable in said head and through the slotted opening in the cap-plate, said pin adapted to engage a stay wire and place it so as to be wrapped around another wire by said head and said cap-plate, an attachment partially encircling said cap-

plate and having a sloping lower surface for guiding the stay wire down into the slot in said cap-plate as the head and cap-plate are revolved and immediately following the engagement of said wire by said pin.

10. In a wire fence machine, in combination, a bed-plate, a coiling head journaled in said bed-plate, a wire depressing member encircling a portion of said head, said member having a sloping lower surface.

11. In a wire fence machine, in combination, a bed-plate, a coiling head journaled in said bed-plate, a bushing for said head, a wire depressing member encircling a portion of said head, the lower surface of said member being removed above the surface of the bushing and being inclined from one end portion thereof.

12. In a wire fence machine, in combination, a bed-plate, a coiling head journaled in said bed-plate, a cap-plate attached to said head, a wire depressing member encircling a portion of said cap-plate with its lower surface spaced above the surface of the head, said lower surface of said member being inclined.

13. In a wire fence machine, a coiling head, a retractable pin in said head, said pin being normally adapted, when said head is rotated, to engage and form a loop in the body of a stay wire to be subsequently wrapped by said head around a wire passing through said head; a wire depressing member associated with said head and having a sloping lower surface, said member adapted, when the end of a stay wire is coincident with said head to depress the stay wire when engaged by the pin, whereby the head will wrap the single end of the stay wire around the wire passing through the head.

14. In a wire fence machine, in combination, a series of twisting devices through which strand wires pass, means for operating said twisting devices, a stay wire feeding means, said feeding means adapted to alternately feed a short stay wire and a comparatively longer stay wire, one of said twistlers adapted to engage and wrap the end of each short stay wire around a certain intermediate strand wire, said twister also adapted to engage an intermediate portion of said comparatively longer stay wire, form a loop therein, and wrap said loop around the said intermediate strand wire, to which the end of each short stay wire is connected.

In testimony whereof I affix my signature, in presence of two witnesses.

CHARLES H. HAISLEY.
